US0D1080627S

(12) **United States Design Patent** (10) Patent No.: **US D1,080,627 S**
(45) Date of Patent: ** Jun. 24, 2025

(54) **KEYBOARD DOCK**

(71) Applicant: **Getac Technology Corporation**, New Taipei (TW)

(72) Inventor: **Shi-Liang Zhong**, Taipei (TW)

(73) Assignee: **Getac Technology Corporation**, New Taipei (TW)

(**) Term: **15 Years**

(21) Appl. No.: **29/856,365**

(22) Filed: **Oct. 13, 2022**

Related U.S. Application Data

(63) Continuation of application No. 29/845,079, filed on Jul. 5, 2022, which is a continuation of application No. 29/844,068, filed on Jun. 27, 2022.

CLAIM

The ornamental design for a keyboard dock as shown and described.

DESCRIPTION

FIG. 1 is a front, top and left side perspective view of a keyboard dock showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1; and,

FIG. 8 is a rear, top and left side perspective view of the keyboard dock.

1 Claim, 8 Drawing Sheets
